Inventor

James Schornack,

By B P Johnson

Attorney

UNITED STATES PATENT OFFICE.

JAMES SCHORNACK, OF PHILADELPHIA, PENNSYLVANIA.

POWER JACK.

Application filed October 12, 1923. Serial No. 668,145.

To all whom it may concern:

Be it known that I, JAMES SCHORNACK, a citizen of the United States, residing at Philadelphia, in the county of Philadelphia and State of Pennsylvania, have invented certain new and useful Improvements in Power Jacks, of which the following is a specification.

My invention relates to power jacks, for 10 automobiles, trucks, or other vehicles, and has particular reference to such a device which is an improvement upon the power jack disclosed in my application filed June 29th, 1923, Serial No. 648,587.

15 In my copending application I have shown a toothed wheel or gear secured to the rear wheel of an automobile, and this gear is arranged to engage with an inclined toothed lifting track. In the construction shown in 20 my copending application, the toothed lifting track is stationary, when placed in position, and it is sometimes difficult to properly locate the lifting tract, over the hole or the like, so that its teeth will engage the teeth 25 of the gear carried by the wheel. To overcome this disadvantage, I have provided the construction shown in the present application.

My present invention comprises generally 30 a toothed lifting track which is vertically adjustable, so that it may be elevated to engagement with the gear carried by the wheel, when supported in proximity thereto, with means to raise and lower the lifting track.

35 In the accompanying drawings, forming a part of this specification, and in which like numerals are employed to designate like parts throughout the same,

Figure 1 is a side elevation of apparatus 40 embodying my invention,

Figure 2 is a plan view of the same,

Figure 3 is a central vertical longitudinal section through the lifting screw and nut, and,

45 Figure 4 is a transverse section through the toothed gear.

In the drawings, wherein for the purpose of illustration is shown a preferred embodiment of my invention, the numeral 5 designates a toothed wheel or gear, which may be cup shaped, to fit over the hub 6 of the rear wheel of an automobile. The gear 5 carries radial arms 7, suitably secured to a disk 8, which is clamped to the wheel. This

construction is shown in my copending application, above referred to, and need not be explained in detail.

The adjustable lifting track embodies a vertical swinging support 9, including an upper rail 10, having a forward inclined 55 raising portion 11, and a rear lowering portion 12. These raising and lowering portions are provided upon their upper surfaces with teeth, for coaction with the guard 5. The support 10 further embodies a lower 60 horizontal rail 13, connected by vertical struts 14, spaced as shown. The lowering portion 12 and the rail 13 converge downwardly and are united in an integral head 15, as shown. The elevating portion 11 and 65 the rail 13 converge rearwardly and lead into an integral head 16, which is forked, as shown. The support 10 is therefore preferably an integral structure.

70 The numeral 17 designates a base, provided near one end with a pair of upstanding apertured ears or knuckles 18, receiving the head 15 therebetween, these parts being pivotally connected by means of a pin 19 or the like. The support 10 is therefore pivotally mounted upon the base 17 to swing in a vertical plane with relation thereto.

75 The base 17 is provided at its rear end with a pair of upstanding apertured ears or knuckles 20, integral therewith, pivotally 80 receiving trunnions 21, carried upon the ends of the block 22. This block has an upstanding screw 23, preferably formed integral therewith. This screw carries an operating nut 24. The screw 23 is slidable 85 within a sleeve 25, carrying trunnions 26, which are pivoted within openings formed in the ends of the apertured head 16.

90 In view of the foregoing description, it will be seen that the base 17 may be arranged in proximity to the wheel to be raised, and if the rail 10 does not engage the gear 5, this rail may be elevated by turning the nut 24 by a suitable wrench, which will elevate the rail, as is obvious.

95 It is to be understood that the form of my invention herewith shown and described is to be taken as a preferred example of the same, and that various changes in the shape, size, and arrangement of parts may 100 be resorted to without departing from the spirit of my invention, or the scope of the subjoined claims.

Having thus described my invention, I claim:

1. The combination with a gear having connection with the driving wheel of a vehicle, a base to be arranged near the wheel, a vertically adjustable support carried by the base and having raising and lowering portions provided with teeth for coaction with the gear, and means to raise and lower the support with relation to the base.
2. The combination with a gear having connection with the driving wheel of a vehicle, of a base to be arranged near the wheel, a vertically movable track secured to the base and having gear teeth for engagement with said gear, and means to raise and lower a portion of the track.
3. A lifting device for coaction with a

gear secured to the driving wheel of a vehicle, comprising a base, a rail pivotally connected with the base to swing in a vertical plane, and means to raise and lower the free end of the rail.

4. A lifting device for coaction with a gear secured to the driving wheel of a vehicle, comprising a base, a rail pivotally connected with the base and having gear teeth, a sleeve pivotally connected with the free end of the rail, a screw pivotally connected with the base and slidable within the sleeve, and a nut carried by the screw and engaging the sleeve.

In testimony whereof I affix my signature.

JAMES SCHORNACK.
